UNITED STATES PATENT OFFICE.

SAMUEL J. YOUNG, OF BROOKLYN, ASSIGNOR TO KIGGINS & TOOKER CO.,
OF NEW YORK, N. Y.

FASTENING-BAND FOR MEMORANDUM-BOOKS.

SPECIFICATION forming part of Letters Patent No. 393,198, dated November 20, 1888.

Application filed April 30, 1887. Serial No. 236,658. (No model.)

To all whom it may concern:

Be it known that I, SAMUEL J. YOUNG, of Brooklyn, in the county of Kings and State of New York, have invented a new and Improved 5 Fastening-Band for Memorandum-Books, of which the following is a full, clear, and exact description.

The object of my invention is to provide a new and improved fastening for books—such as memorandum-books—which fastening gives a neat appearance to the book, and is durable and reliable, holding the book securely closed.

The invention consists of a memorandum-book provided on the inside of one cover with 15 a cross-piece or pocket for the reception of the leaves and the other cover.

Reference is to be had to the accompanying drawings, forming a part of this specification, in which similar letters of reference indicate 20 corresponding parts in all the figures.

Figure 1 is a perspective view of my improvement in an open position. Fig. 2 is a similar view of the same, showing the book in a closed position; and Fig. 3 is a perspective view of 25 part of a modified form of my improvement.

Heretofore books—such as memorandum-books, &c.—were locked in a closed position by clasps or elastic bands secured to one cover and passed over the other cover after the book 30 had been closed; but the clasps were easily broken and liable to tear the pockets in which the books were carried, and the elastic bands were soon worn out, losing their elasticity, and were also liable to be torn off. With my im- 35 proved fastening, presently to be described, I avoid these difficulties and provide a reliable fastening, which gives a neat appearance to the book.

The book A is provided with the covers B and C, between which are held, in any suitable 40 manner, the leaves D. Near the outer end of the cover B, and on the inside of the same, is formed a U-shaped cross-piece, E, which may be closed at its outer end to form a pocket, as shown in Figs. 1 and 2, or it may be open, as 45 illustrated in Fig. 3. The cross-piece E extends from one side of the cover to the other, and is of sufficient width and height to admit the outer ends of the leaves D and the cover C, which, when passed under the cross-piece E, 50 as shown in Fig. 2, are locked to the cover B, whereby the book is securely held in a closed position.

The cross-piece E can be made of leather, card-board, sheet metal, or other suitable material. A separate pocket or loop may be 55 formed on the outside of the cross-piece E or on the edges or backs of the covers B and C for the reception and retention of the pencil.

Having thus described my invention, what I 60 claim as new, and desire to secure by Letters Patent, is—

As an improved article of manufacture, a memorandum-book provided with a non-elastic 65 pocket or band at or near the outer end of one of its covers and situated on the inside thereof, the said pocket or band being of sufficient height and width to admit the outer end of the leaves and the other cover, as set forth.

SAML. J. YOUNG.
